UNITED STATES PATENT OFFICE.

GEORGE W. WHEELWRIGHT, OF NEWARK, NEW JERSEY, ASSIGNOR TO AMERICAN CAN COMPANY, OF NEW YORK, N. Y., A CORPORATION OF NEW JERSEY.

ARTICLE-FEEDING MECHANISM.

1,330,964.

Specification of Letters Patent.

Patented Feb. 17, 1920.

Application filed April 17, 1916. Serial No. 91,776.

To all whom it may concern:

Be it known that I, GEORGE W. WHEELWRIGHT, a citizen of the United States, residing at Newark, in the county of Essex and 5 State of New Jersey, have invented certain new and useful Improvements in Article-Feeding Mechanism, of which the following is a specification.

This invention relates to mechanism for 10 separating and discharging single articles successively from a positioned supply of articles, and is adapted to operate in conjunction with any machine that performs some operation on articles successively.

15 The invention comprises positive mechanism for selecting and discharging a single article, such, for example, as a can end, and is so connected and operated that its action will be unfailing and perfectly timed.

20 As illustrated in the accompanying drawings I have shown it separate from an operating machine, but have illustrated means for connecting it to a moving part of such a machine.

25 In the drawings:

Figure 1 is a plan view of a supporting plate on which are mounted interconnected rocking members and means for maintaining a positioned supply of can ends.

30 Figs. 2 and 3 are similar views showing the operating parts in different positions.

Fig. 4 is a vertical sectional view taken on line 4—4 of Fig. 1.

Fig. 5 is a side view taken in direction 35 of the arrow 5 on Fig. 2.

Fig. 6 is a right angle sectional view taken on line 6—6 of Fig. 3.

Fig. 7 is a right angle sectional view taken on line 7—7 of Fig. 2.

40 Fig. 8 is a right angle sectional view taken on line 8—8 of Fig. 1.

Fig. 9 is a diagrammatic view showing the line of movement of the separating and discharging members 7', 8', 9' and 10'.

45 The entire feed mechanism is mounted on a plate or bed 1 having an opening through which the articles are discharged; four rods 2 form a vertical stack support; arranged approximately equidistant are four

50 rocking members 3, 4, 5, and 6 connected by links 7, 8, 9 and 10. The rocker 3 has an arm 3' and an operating link 3'' which is attached to a moving part of a machine.

The separating elements of this device are the links 7, 8, 9 and 10 carrying knife edge 55 members 7', 8', 9', and 10'; the links 7 and 9 constitute a pair and the links 8 and 10 constitute an alternate pair. The knife edge separators 7' and 9' lie in a plane at a distance equal to the thickness of a can end or 60 other article, below the separators 8' and 10'.

In Fig. 1 the rockers 3, 4, 5 and 6 are shown at one limit of their stroke, the spring 11 being under tension, and the separators 8 and 10 extending under the stack 65 and supporting it as shown at 8, Fig. 8, while the separators 7 and 9 are outside the zone of the stack, as shown at 9, Fig. 8. As the link 3 moves in the direction of the arrow, Fig. 1, the rockers 3, 4, 5 and 6 will 70 move in the direction of the arrows as shown, and the links 7 and 9 carrying the knife edge separators 7' and 9' will move under the stack of can ends and the members 8' and 10' will move away from the 75 stack.

The path of travel of the members 7', 8', 9' and 10' is graphically illustrated in Fig. 9.

Figs. 1, 2 and 3 show the changing positions of the various parts as the change 80 progresses in a complete movement of the device; the pairs 7 and 9 alternate with the pairs 8 and 10 in working within and without the zone of the can end stack, the operation being as follows: Fig. 1 and Fig. 8 85 are companion views; the pair of elements 7 and 9 are outside the stack zone and the pair of elements 8 and 10 are within the stack zone, and by reference to Fig. 8 a can end has just been released and is falling 90 away from the bottom of the stack. A movement of the parts from their positions in Fig. 1 to that shown in Figs. 2 and 3 and back again to Fig. 1 would repeat the cycle and drop another can end. After the can end 95 has dropped away as shown in Fig. 8 the pair of elements 8' and 10' are supporting the stack and just beginning to move away from the stack and the pair 7' and 9' will move into the stack; as the elements 8' and 10' release the stack it will drop down onto the elements 7' and 9' a distance equal to the thickness of one can end and be thereby supported until the elements 8' and 10' again enter the stack as at Fig. 7 and support the same, leaving the lowermost end 105

free to drop as soon as released by the elements 7' and 9'. The alternate rocking position given to the elements, 7', 9', 8' and 10' produces a successive dropping of single can ends.

5 The spring 11 is not needed where the link 3" is connected to positive moving mechanism but would be necessary where the arm 3' was deflected by passing mechanism; 10 where it was so deflected the normal position of the mechanism would be as in Fig. 3.

What is claimed is:—

1. In an apparatus for releasing individual articles; a support for a stack of articles; a plurality of pairs of rocker members mounted adjacent said support; and link members connecting said rocker members in alternating pairs, whereby as the 20 rocker members are moved, the alternating link members move into and out of the zone of the stack of articles, whereby a single article is released.

2. In an apparatus for releasing individual articles; a support for a supply of superposed articles; rocker members mounted adjacent said support; a plurality of pairs of links connecting said rocker members; and separating and releasing members carried by said links, whereby as the said rocker members are moved the said separating members alternately support the said supply of articles and operate to separate and release an individual article.

3. An apparatus for releasing individual articles from a supply of articles, comprising means for supporting a supply of individual articles; and rocking means operating and controlling oppositely disposed and 40 alternately acting releasing means, all the parts of said rocking means having links which connect them all together, whereby at each complete cycle of movement of said rocker means an individual article is released from said supply.

4. An apparatus for releasing individual articles from a supply of articles, comprising members for supporting a supply of individual articles; rocking means operating 50 and controlling oppositely disposed and alternately acting releasing means comprising links that engage the articles at points between the pivots of the links, whereby at each complete cycle of movement of said rocker means an individual article is released from said supply.

5. An apparatus for releasing individual articles from a supply of articles, comprising means for supporting a supply 60 of individual articles; and rocking means operating and controlling oppositely disposed and alternately acting releasing means comprising links that engage the articles at points between the pivots of the links, whereby at each complete cycle

of movement of said rocker means an individual article is released from said supply, while the supply is supported by one of the alternately acting releasing means.

6. An apparatus for releasing individual articles from a stack, comprising means for maintaining a stack of individual articles; and pairs of rocking members all connected together and simultaneously moving and controlling oppositely disposed and alternately acting releasing and stack supporting means, whereby at each complete cycle of movement of said rocker means an individual article is released from said supply.

7. An apparatus for releasing individual articles from a supply of articles, comprising means for maintaining a supply of individual articles; and rocking means pivotally attached to links which constitute oppositely disposed, alternately acting releasing means, said links being pivoted at both ends to said rocking means, whereby at each complete cycle of movement of said rocker means an individual article is released from said supply.

8. An apparatus for releasing individual articles from a supply of articles, comprising means for maintaining a supply of individual articles; and a plurality of pairs of rocking members, and pivotally connecting links which constitute oppositely disposed, alternately acting releasing means that engage the articles, whereby at each complete cycle of movement of said rocker members an individual article is released from said supply.

9. An apparatus for releasing can ends from the bottom of a stack: comprising supports for maintaining a stack of can ends; and pairs of rocking members and links connected with said rocking members and constituting alternately acting releasing means having projecting members arranged at points between the pivots of the links to enter between individual articles and separate and release them from the said stack.

10. In combination; a can end stack support; a plurality of pairs of rocking members arranged about said support and pivotally mounted; links pivotally connecting said rocker members; and can end separating means carried by said links and adapted to be moved between superposed can ends in said support.

11. In combination: pairs of can end supporting and releasing devices arranged alternately around a circle, each of said devices having a pivotal support at both ends, and means for moving said supports alternately toward and from the center to release successive can ends.

12. In combination: pairs of rocking arms arranged alternately around a circle, means for pivotally supporting said arms, and can end supporting and releasing de-

vices, pivotally connecting said arms in pairs and oppositely movable inward and outward thereby to release successive can ends.

- 5 13. The combination of a stack holding means, rocker arms having fixed pivots and arranged around said stack holding means, links extending from one rocker arm to another and pivotally connected therewith,
10 and article-separating and supporting members carried by said links, whereby the oscillation of the pivoted system of said arms and links causes the alternate inward and outward movement of said separating and

supporting members and the feed of articles 15 from a stack of the same.

14. The combination of article - holding means and article-separating means, and a system of alternating rockers and links all movably connected with each other, each 20 rocker being connected with two links and each link being connected with two rockers, and connected with said article-separating means, to actuate the latter for the feeding of articles from said holding means. 25

In testimony whereof I affix my signature.

GEORGE W. WHEELWRIGHT.
